Primary Examiner — Keith J Wilson(74) *Attorney, Agent, or Firm* — Ladas & Parry, LLP(57) **CLAIM**

The ornamental design for a water electrolyze apparatus, as shown and described.

DESCRIPTION

FIG. 1 is a perspective view of a water electrolyze apparatus showing the claimed design;

FIG. 2 is a front view of the water electrolyze apparatus showing the claimed design;

FIG. 3 is a rear view of the water electrolyze apparatus showing the claimed design;

FIG. 4 is a left side view of the water electrolyze apparatus showing the claimed design;

FIG. 5 is a right side view of the water electrolyze apparatus showing the claimed design;

FIG. 6 is a top view of the water electrolyze apparatus showing the claimed design; and,

FIG. 7 is a bottom view of the water electrolyze apparatus showing the claimed design.

The broken lines shown in the figures show portions of a water electrolyze apparatus which form no part of the claimed design.

1 Claim, 7 Drawing Sheets(56)
